UNITED STATES PATENT OFFICE.

ARTHUR EDWARD LARSON, OF CHICAGO, ILLINOIS.

TOY ADDING MACHINE.

1,414,655.

Specification of Letters Patent. Patented May 2, 1922.

Application filed February 7, 1921. Serial No. 443,129.

To all whom it may concern:

Be it known that I, ARTHUR E. LARSON, a citizen of the United States, and a resident of the city of Chicago, in the county 5 of Cook and State of Illinois, have invented a new and useful Improvement in Toy Adding Machines, of which the following is a full, clear, and exact description.

My invention relates to improvements in 10 toy adding machines, and it consists in the combinations, constructions and arrangements, herein described and claimed.

An object of my invention is to provide 15 a toy adding machine which resembles a regular adding machine and which will accurately add small numbers.

A further object of my invention is to 20 provide a toy adding machine which is simple in construction and operation.

25 A further object of my invention is to provide a device of the type described having means for quickly resetting the machine back to zero.

30 A further object of my invention is to provide a device of the type described that can readily add any amount up to ten with each operation.

35 A further object of my invention is to provide a device of the type described having few parts and which is cheap to manufacture.

40 Other objects and advantages will appear in the following specification, and the novel features of the invention will be particularly pointed out in the appended claim.

45 My invention is illustrated in the accompanying drawings, forming part of this application, in which—

Figure 1 is a side elevation of the device,
40 Figure 2 is an end elevation of the device,

Figure 3 is a top plan view with a portion of the casing removed, and

Figure 4 is a section along the line 4—4 of Figure 1.

50 In carrying out my invention, I provide a casing comprising end walls 1 and 2 spaced from each other by a plate which is bent so as to form the side wall 3, the semi-cylindrical top 4 and the side wall 5 of the casing. Disposed in the casing and rotatably carried by the end walls 1 and 2 thereof, is a shaft 6 which is held from longitudinal movement by the nuts 7 and 8 that are mounted on its threaded ends. To facilitate the turning of the shaft 6 in the casing, 55 I mount a hand-wheel 9 adjacent the nut 8

and rigidly secure it to the shaft 6 by means of a nut 10 and the nut 8.

Rigidly secured to the shaft 6 by a set screw 11 is a disc 12 having on its periphery 60 a plurality of numbers 13 preferably consecutively numbered from one to one hundred, and having a plurality of teeth 14 adjacent its periphery and projecting outwardly from one of its sides, each of the 65 teeth being disposed opposite a number. The disc 12 is adapted to rotate counter-clock-wise as shown by the direction of the arrow in Figure 2. Obviously the disc 12 can be rotated by turning the hand-wheel 9, 70 since both the hand-wheel and the disc are rigidly secured to the shaft 6. An opening 15 is provided in the side 3 of the casing just above the periphery of the disc 13 and is of such a width that only one of the numbers on the disc can be seen therethrough at one time.

Rotatably disposed in the casing and positioned adjacent the opening 15 is a peg 16 that has a disc 17 mounted thereon and 80 which is rigidly held by two nuts 18. As will be seen in Figures 1 and 4, the disc 17 is mounted underneath the casing and has a plurality of numbers imprinted on the surface that is adjacent the casing, any one 85 of the numbers being adapted to register with the opening 15.

A means for rotating the disc 12 for any predetermined distance is provided, and comprises a wheel 19 which is loosely mounted on the shaft 6. The wheel 19 is adapted to be moved by means of a handle 20 which is mounted adjacent the periphery thereof and extends through an arcuate slot 21 in the end wall 2 of the casing. The handle 20 is provided with a pointer 22 that is bent up and over the casing as is clearly shown in Figures 1 and 2. A plurality of consecutively arranged numbers 23 are imprinted on the casing and are positioned adjacent the end of the pointer 22. It should be noted that the spaces between the numbers on the disc 12 and between the numbers 23 on the casing are equal.

Movement is imparted from the wheel 19 to the disc 12 by means of a pawl 24 which is pivotally secured between lugs 25 projecting from the wheel 19. A spring 26 yieldingly retains the pawl 24 in engagement with the teeth 14 of the disc 12. A 110 second pawl 27 diametrically opposed to the pawl 24 is pivotally mounted on a pin 28

which is carried by a plate 29. The pawl 27 is yieldingly kept in engagement with the teeth 14 by means of a spring 30.

From the foregoing description of the various parts of the device, the operation thereof may be readily understood. When one wishes to add any number, as for example three, to the sum total shown, as one hundred and ten in Figure 1, he moves the handle 20 in a clockwise direction in the arcuate slot 21, carrying with it the pointer 22 and the wheel 19. The wheel 19 is rotated until the pointer 22 is directly above the figure three of the numbers 23. The pawl 24 10 is carried around with the wheel 19 and since the pawl 27 prevents the disc 12 from rotating in a clockwise direction, the pawl 24 will ride over three of the teeth 14 of the disc 12. Returning the handle to its normal position 15 causes the wheel 19 to rotate in a counterclockwise direction, the pawl 24 to engage the teeth 14 and to also rotate the disc 12 in a counterclockwise direction while the pawl 27 rides over three of the teeth 14. This movement adds three to the total. It will be observed that the numbers on the disc 17 designate hundreds, while the numbers on the disc 12 20 designate digits.

The machine can be readily turned back 30 so as to register zero when the addition has been completed. This is accomplished by turning the hand-wheel 9 in a counterclockwise direction until the zero on the periphery of the disc 12 is in registration with the 35 opening 5. The handle 20 performs a double

function in that it is the means by which the wheel 19 is rotated and is also the means for preventing the rotation of the wheel when the disc 12 is reset, since the handle abuts against the end of the arcuate slot. The peg 40 16 can also be rotated so as to bring the zero on the disc 17 into registration with the opening 15. The machine is now ready for another addition.

This device is very simple in construction 45 and operation, has few moving parts and can be manufactured at a cheap price.

I claim:

A toy adding machine comprising a casing having a cylindrical-shaped top, and having 50 an arcuate slot in one side thereof, a shaft carried by said casing, a disc carried by said shaft, a second disc rotatably carried by said casing, said second named disc being disposed adjacent to said first named disc, and 55 having numbers thereon, said casing having an elongated opening adapted to show only one number on each of said discs at a given time, a wheel secured to said shaft, said wheel when oscillated being adapted to rotate said first named disc, an arm carried by 60 said wheel and projecting through the arcuate slot, a series of numbers on the outer cylindrical surface of said casing, said last 65 named numbers being spaced the same distance apart as the numbers on said first named disc, and a pointer carried by said handle and being disposed over the numbers on said casing.

ARTHUR EDWARD LARSON.
